UNITED STATES PATENT OFFICE.

MELVILLE A. GUNST, OF NEW YORK, N. Y., ASSIGNOR TO MELVILLE A. GUNST
COSTUME CO., A CORPORATION OF NEW YORK.

DESIGN FOR A TEXTILE FABRIC.

Application filed March 3, 1925. Serial No. 12,566. Term of patent 3½ years.

To all whom it may concern:

Be it known that I, MELVILLE A. GUNST, a citizen of the United States of America, and a resident of the city of New York, county of New York, and State of New York, have invented a new, original, and ornamental Design for a Textile Fabric, of which the following is a specification, reference being had to the accompanying drawing, forming part thereof.

The figure is a plan view of a textile fabric, illustrating my new and ornamental design.

I claim:

The ornamental design for a textile fabric, as shown.

MELVILLE A. GUNST.
